HYDRAULIC FUSE

Emmett C. Hartley and Harry B. Carbon, Cleveland, Ohio, assignors to The Parker Appliance Company, Cleveland, Ohio, a corporation of Ohio

Application November 22, 1944, Serial No. 564,640

3 Claims. (Cl. 251—146)

1

The invention, of which the following is a detailed description, relates to a safety fuse for hydraulic pressure lines, sometimes referred to as a hydraulic fuse. The general purpose of such devices is to cut off promptly the flow of pressure fluid, oil or the like, in piping where the latter is suddenly broken. As an example it may be pointed out that hydraulic operating lines are customarily used on airplanes for the control of wings, ailerons, rudders, elevators and the like. In the event that the high pressure piping is broken it is necessary to seal the broken line to prevent loss of fluid and disturbances of the operating circuits.

One of the objects of our invention is to permit a normal flow of fluid under pressure in an operating pipe circuit. It is also important that normal operation be not disturbed by momentary surges of abnormal or excess flow and this is amply provided for by our improvement.

The object of our invention includes however means by which a continued excess of flow will result in a throttling action to restrict the volume of fluid permitted to pass the valve or fuse.

A further object of our invention is to effect closure, stoppage or sealing off of the discharge side of the tubing immediately following a break in that line and the loss of a material and predetermined quantity of fluid.

Another object of our invention is to restrict the loss of pressure fluid on the occasion of a rupture to a relatively constant small quantity regardless of the range of pressure by which the fluid may be delivered to the piping.

It is a still further object of our invention to calibrate the hydraulic fuse to a suitable amount determined by the volume for the device being actuated. Thus where the pressure fluid is being delivered to the cylinder of a reciprocating piston, the volume of the cylinder may be used to determine the action of the fuse. For this purpose the fuse may be calibrated to permit enough fluid to operate the cylinder even in the event of moderate leakage but to stop the flow after a volume has been delivered sufficient to fill the cylinder.

Incidental to the objects of our invention it is also intended to effect a prompt return to the normal open position of the fuse when there is no further escape of the liquid, or when, under some operating conditions, the direction of fluid pressure is reversed.

For purpose of illustration we have shown the preferred form of our invention in the accompanying drawings in which:

2

Figure 1 is a side elevation partly in longitudinal section, of the improved fuse in its open position:

Fig. 2 is an elevation of the inlet end;

Fig. 3 is a vertical section on the line 3—3 of Fig. 1;

Fig. 4 is a vertical section on line 4—4 of Fig. 1, and

Fig. 5 is a side elevation, partly in longitudinal section of the fuse in its closed position.

Generally speaking this hydraulic fuse forms part of a line of piping through which fluid is conveyed under pressure for use in operating a piston or the like to produce reciprocating motion.

10 The piping system is not illustrated as it is conventional and forms no part of the invention.

The fuse comprises a casing, housing or body member 6. This may be interposed in the fluid pressure tubing by means of end fittings. End fitting 7 is a cap which is bolted upon the discharge end of the body member by means of a flange 8 and appropriate bolts 9. The fitting is sealed to the end of the body member 6 by means of a packing 10 which is seated in a peripheral groove 11 of the fitting or end cap.

20 The cap is internally screw-threaded as at 12 and has a series of passageways 13 connecting the central bore with the inner face of the cap. A circular groove 14 connects with the inner ends of the passageway 13.

30 The inner face of the cap 7 is spaced from the opposite wall of the body member 6 to receive a suitable valve seat 15. This is in the form of a disk of rubber or other elastic material which is not affected by the pressure fluid being used.

35 The disk has a circular series of openings 16 opposite the groove 14. The thickness of the disk is such that it will not be distorted but will maintain a substantially plane valve surface. By reason of the provision of groove 14 no care need be

40 exercised to maintain unrestricted flow between the passageways 13 and the openings 16 as unrestricted flow will be assured by the circular groove 14. The body 6 has a central bore in the form of a cylinder 17. One edge of this bore fits against the valve disk 15.

45 The opposite end of the valve cylinder 17 terminates in a dash-pot chamber 18 of substantially greater diameter and cross sectional area. This chamber extends towards the opposite ends of the member 6. At the point where the chamber 18 meets the cylinder 17, the chamber is under-cut to form an enlarged bore 19.

50 This end of the member 6 is closed by means of a cap or fitting 20. It is screw threaded

internally as at 21 and has a flange 22 by which it is bolted on the end of the body 6 with bolts 23.

The cap has a peripheral groove 24 accommodating a packing 25 by which the cap is sealed to the body.

A freely sliding valve member 26 is provided in the area of the cylinder 17 and the chamber 18. The valve 26 is generally cylindrical and provides a sliding fit along the inner wall of the cylinder 17. The opposite end of the valve has an outwardly directed flange 27 which extends to the cylindrical wall of the chamber 18. On its outer edge the flange 27 is chamfered to reduce contact with the chamber surface. At the same time very close clearance is maintained between these two surfaces being of the order of one to two thousandths of an inch. Thus there is slight, if any leakage of pressure fluid around the flange. A series of metering openings 28 pass through the flange 27 and connect the chamber 18 with the inlet end of the fuse.

The valve 26 is held in normal open position with the flange 27 resting against the cap 21 by means of a coil spring 29.

Check valves are provided between the chamber 18 and the axial bore 30 of the valve 26. These check valves consist of one or more radially disposed recesses 31. Each such recess terminates in a port 32 connecting with the bore 30. A ball valve 33 is loosely contained in the recess 31 and may seal the discharge to the bore 30 by fitting against the edge of the port 32. In order to prevent dislodgment of the ball valve 33 a split ring retainer 34 is carried in a peripheral groove around the outer surface of the valve 26.

Figure 1 shows the fuse in its open or normal operating position. When it is installed in a line of piping which is filled with fluid under pressure, the latter immediately fills not only the bore 30 but also the cylinder 17, the dash-pot chamber 18 and the enlargement 19. In this position the pressure is balanced between the chamber 18 and the cylinder 17 so that the ball valves 33 are free to remain open. In this position and in the absence of the discharge of fluid pressure against the inlet of the fuse, there is no differential in the pressure at the inlet and the outlet.

When fluid is admitted under pressure to carry out the operating effect in the line beyond the outlet, it acts across the area of the front face of the valve member 27 tending to move the valve toward the seat 15. An additional force for closing the valve is provided by the frictional and impingement effect of the moving fluid upon the valve 26 as it passes therethrough. The pressure fluid also acts across the rear face of the valve which is opposed to the seat 15, tending to keep the valve open. The unit pressure acting on the rear face will be less than that acting on the front face because there will be drop in pressure as the fluid passes through the passage 30, and since the total area of the ports 16 is greater than the area of the valve passage 30 there is no restriction beyond the passage 30 to cause a pressure rise.

Since the area of the rear face is smaller than the area of the front face, and since the unit fluid pressure is greater upon the front face than upon the rear face, and because of the frictional effect, the valve 26 will move toward the seat against the action of the spring 29.

Closing movement of the valve is resisted by the dash pot, the pressure of the fluid within the dash pot chamber building up so as to close the check valve 32 and leaving only the metered open-

ings 28 through which the fluid can escape from the dash pot chamber.

There is then no escape for the fluid under pressure in the chamber other than through the metering passageways 28 in the flange 27. It may be stated at this point that the pressure of the fluid against the flange 27 overcomes the coil spring 29 incidental to the discharge of fluid through the passageways 28.

10 The valve 26 moves slowly at a predetermined rate of speed toward the valve seat 15.

Normally the volume of pressure fluid desired to be used in the operating circuit beyond the outlet will have passed beyond the outlet before the 15 valve 26 passes beyond the normal part of the chamber 18. Therefore the flow of pressure fluid is cut off before the valve 26 completes its closing movement. Immediately a balance of pressure develops between the inner chamber of the fuse 20 and the chamber 18 resulting in the coil spring then driving the flange 27 back to the open position against the inlet fitting.

When however the flow through the outlet, due to leakage or rupture of the piping is excessive,

25 then the valve 26 continues to move towards its seat far enough to bring the flange 27 opposite the enlargement 19. At this point the discharge from the dash-pot and the enlargement 19 is no longer restricted by the metering openings 28. 30 Consequently the valve 26 is brought against the valve seat 15 by a rapid movement such that the outlets 16 are adequately closed.

It is to be noted that as soon as the pressure in the dash-pot and its enlargement 19 is restored 35 to that in the bore 30, the lower ball 33 will fall away from the valve seat 32.

As long as the discharge line is ruptured, the pressure of the fluid in the fuse will hold the valve 26 on its seat 15 and thus prevent further 40 loss of fluid. This is illustrated in Figure 5.

As soon as operating conditions are restored in 45 the discharge line the difference in pressure no longer exists and the spring 29 brings the valve back to its open position. This arrangement of the valve permits ready adjustment for different operating conditions. Thus if the cylinder on the discharge end of the fuse varies from ten to twenty or forty cubic inches, a similar change in 50 the number of the metering openings 28 is called for. These openings may be assumed to be one thirty-second of an inch in diameter. The flow through the fuse may vary from one to six gallons a minute. At the same time the pressure of the 55 fluid may range from one hundred to one thousand pounds per square inch. It has been found that with a cylinder of forty cubic inches two such metering holes will be sufficient when used with a one-half inch tube line to cause the valve or fuse to close with loss of only fifteen to eighteen fluid ounces of fluid.

60 Increasing the number of holes to three will accelerate the closing of the valve in case of rupture so that only from ten to fourteen fluid ounces are lost regardless of variation in pressure of from one hundred to one thousand pounds per square inch.

In like manner five metering holes in the flange 65 check a loss of fluid of from five to eleven fluid ounces, over the same pressure arrangement.

70 From these results it is evident that regardless of the actual pressure or of the rate of flow of the fluid the fuse operates to close the broken line after a relatively constant amount of fluid has passed therethrough.

75 It is an important feature of the improvement

that this throttling and sealing operation is effective only in one direction. Frequently reciprocation of the piston in the operating cylinder will drive the pressure fluid through the fuse in the reverse direction. Thus it will not be delayed or impeded because the spring 29 will already have lifted the valve from its seat and brought it into open position where it is instantly available for use in throttling or limiting the flow of fluid when next passed through in the normal direction.

It will be evident that our invention has secured the above and other incidental objects in an effective manner and that the arrangement is durable, economical of manufacture and replacement. Various changes may be made in minor details in arrangement and materials without departing from the scope of the invention as defined in the following claims.

We claim:

1. A hydraulic fuse comprising a cylinder, an aligned concentric chamber of a diameter larger than the cylinder, an inlet cap on the chamber, an outlet cap on the cylinder, a valve seat associated with said outlet cap, an axially bored valve member freely slideable in the cylinder and adapted to engage said seat, a peripheral flange on the inner end of the valve member and slidably fitting the wall of the chamber, metering openings through said flange, check means in the valve member beyond the flange to prevent fluid flow from the chamber to the bore of the valve member but permitting reverse flow, said chamber being enlarged at its end adjacent the cylinder to provide increased clearance for the flange as the valve member approaches the valve seat, spring means for retracting the valve member when the pressure is equalized between the cylinder and the chamber, and registering ports in the outlet cap and valve seat providing sufficient fluid discharge to lower the pressure in the cylinder below that on the flange end of the valve member to overcome the retracting spring and cause the valve member to contact the valve seat.

2. A hydraulic fuse comprising a cylinder, an aligned concentric chamber of a diameter larger than the cylinder and connected therewith by a laterally extending shoulder, an inlet cap on the chamber, an outlet cap on the cylinder, a valve seat associated with said outlet cap, an axially bored valve member freely slideable in the cylinder and adapted to engage said seat, a peripheral flange on the inner end of the valve member and slidably fitting the wall of the chamber, metering openings through said flange, check means in the

valve member beyond the flange to prevent fluid flow from the chamber to the bore of the valve member but permitting reverse flow, said chamber being enlarged at its end adjacent the laterally extending shoulder to provide increased clearance for the flange as the valve member approaches the valve seat, compressible spring means between the laterally extending shoulder and the flange, and registering ports in the outlet cap and valve seat providing sufficient fluid discharge to lower the pressure in the cylinder below that on the flange end of the valve member to overcome said spring and cause the valve member to contact the valve seat.

3. A hydraulic fuse comprising a cylinder, an aligned concentric chamber of a diameter larger than the cylinder, an inlet cap on the chamber, an outlet cap on the cylinder, a valve seat associated with said outlet cap, an axially bored valve member freely slideable in the cylinder and adapted to engage said seat, a peripheral flange on the inner end of the valve member and slidably fitting the wall of the chamber, metering openings through said flange, ball check valves disposed radially of the valve member beyond the flange, a split ring retainer for the balls of the check valves, said chamber being enlarged at its end adjacent the cylinder to provide increased clearance for the flange as the valve member approaches the valve seat, spring means for retracting the valve member when the pressure is equalized between the cylinder and the chamber, and registering ports in the outlet cap and valve seat providing sufficient fluid discharge to lower the pressure in the cylinder below that on the flange end of the valve member to overcome the retracting spring and cause the valve member to contact the valve seat.
